UNITED STATES PATENT OFFICE.

LEWIS D. STOCKING, OF MILWAUKEE, WISCONSIN, AND ALEXANDER F. WINTERS AND JOHN R. WARREN, OF GRAND RAPIDS, MICHIGAN, ASSIGNEES, BY MESNE ASSIGNMENTS, OF TWO-THIRDS TO SAID STOCKING, ONE-SIXTH TO SAID WINTERS, AND ONE-SIXTH TO ALBERT A. STRYKER, OF GRAND RAPIDS, MICHIGAN.

PAPER-FEEDING MECHANISM FOR TYPE-WRITERS.

1,182,052.

Specification of Letters Patent.

Patented May 9, 1916.

Application filed June 4, 1914. Serial No. 542,829.

To all whom it may concern:

Be it known that we, LEWIS D. STOCKING, ALEXANDER F. WINTERS, and JOHN R. WARREN, all citizens of the United States, said 5 STOCKING residing at Milwaukee, in the county of Milwaukee and State of Wisconsin, and said WINTERS and WARREN residing at Grand Rapids, in the county of Kent and State of Michigan, have invented new 10 and useful Improvements in Paper-Feeding Mechanism for Type-Writers, of which the following is a specification.

Our present invention relates to paper-feeding mechanism for typewriters, and its 15 object is to provide an improved mechanism of that character which shall be simple and economical in construction and easy and efficient in operation; and further, to provide in such mechanism a movable member 20 adapted to engage each successive adjacent paper of the paper body severally and both feed the same to and convey the same from the platen; and further, to provide improved guides for papers; and further, to 25 provide such a feeding mechanism which may be readily applied to different typewriters; and further, to provide improved means for adjusting such mechanism to papers of different thicknesses; and further, 30 to provide improved means for adjusting such mechanism to papers of different dimensions; and further, to provide an improved paper holder to receive the papers from the platen; and further, to provide 35 improved means for operating such mechanism in connection with the platen's rotation; and further, to provide the foregoing in combinations; and further, to provide such 40 mechanism with various new and useful improved devices. These, and any other objects appearing hereinafter, are attained by, and the invention finds a preferable embodiment in, the structure hereinafter described and illustrated in the accompanying 45 drawings, in which:—

Figure 1 is a front view of our paper feeding mechanism and of a portion of a typewriter to which the same has been attached; Fig. 2 is a right-hand side view of 50 the same; Fig. 3 is a central transverse vertical section of the same, certain parts,—the casing plate 40, etc.,—being broken away, and papers (envelops) being shown in va-

rious positions as operated on by the mechanism: Fig. 4 is a fragmentary side view of 55 certain parts; Fig. 5 is a fragmentary axially-sectional view of a chuck and connected parts, whereby the mechanism is manually operated; Fig. 6 is a view of a clamp for holding the lateral members of 60 the secondary frame in relatively adjusted position; Fig. 7 is a side view of a device to prevent lifting the platen during the operation of the feeding mechanism; Fig. 8 is a side view of a base carried by the typewriter 65 and of a member of the frame of our mechanism, illustrating a detachable connection between such base and member; Fig. 9 is a front view of a guide for the papers; and Fig. 10 is a rear view of our paper feeding 70 mechanism.

The frame of our paper feeding mechanism is supported in connection with the typewriter's platen: In the construction shown, this frame comprises supports 1 secured to a base 2 which is adapted to be attached to the particular kind or make of typewriter 3 with which our feeding mechanism is to be used. The supports 1 are adjustable toward and away from each other 75 to accommodate the mechanism to typewriter carriages 4 of different widths, as by the sliding engagement of one or both of the supports on suitable connecting members, which in the form illustrated are the feed- 80 operating shaft 5 and guide rod 6. That our feeding mechanism may be readily removable from the typewriter, suitable 85 detachable connections for said frame and base are provided: Preferably, these are mutually 90 engaging members 7 and 8—essentially mortise and tenon members—whereby the parts are held in predetermined or fixed relation, being securely held therein as by a binding screw 9. The supports 1 sustain the said 95 feed-operating shaft 5 and guide rod 6, both being parallel with the axis of the platen 41. A secondary frame comprising lateral members 10 is supported and slidable on said shaft and guide-rod in order to adjust the 100 mechanism to papers, (as envelopes to be addressed on the typewriter, etc.,) of different dimension in the direction of the writing, said lateral members being secured in such adjusted position by screw clamps 30. A 105 movable member, a belt 11, adapted to en-

gage the papers and to move them relatively to the platen, and preferably of rubber with a fabric or non-stretchable inner portion, is carried on and driven by the roll 12 mounted 5 on each said lateral member and splined on the shaft. The bands are also carried on suitable idler rolls or pulleys 13 suitably disposed and pivoted on said lateral members. Coöperating guides 14 adapted to hold the 10 papers, (as the envelopes 15) to be operated on by our mechanism and the typewriter itself, are carried by the respective lateral members and are adapted to guide such papers to the bands under the pressure of the 15 followers 16, spring-pressed for that purpose as shown and having a sliding movement in follower guides—the slots 17 in the guides 14. Each follower has also a slightly rotatable movement on its guide pin 18 when 20 at the rear portion of the slots 17, so that the follower may be thus slightly turned to engage its part,—the lug 19—with a corresponding co-engaging part of the slot,—viz., the stop or shoulder 20, thus to hold the follower 25 in its rearward position while papers are being placed in the guides. This follower is so guided as to press the paper-body 21 (viz., the mass of papers held in the guides) against the tangential portion 22 of the band, thus to insure their engagement 30 thereby. These guides 14 are minutely adjustable toward and away from the bands to accommodate papers of different thicknesses and to feed them severally, as by the screws 35 23 operating to slightly turn such guides on their pivotal mountings 24.

The feeding mechanism is actuated in connection with the rotation of the platen, as by the sprocket chain 25 carried by the 40 sprocket wheel 26 on the platen and by the sprocket wheel 27 on the feed-operating shaft.

To prevent the lifting of the platen relatively to the carriage (as may be done in 45 some typewriters) by the turning of the platen which draws on the rearward portion 42 of the chain, the connected arms 28 are provided, adapted to rock at their free ends relatively to the axes of the platen and the 50 feed-operating shaft respectively, and carrying the chain-engaging roll 29 as shown. As the drawing tension on the portion 42 of the chain increases, the roll 29 is thereby forced inwardly or forwardly, this straightening the arms to some degree and thereby 55 holding the wheel 26 and the platen from rising. The papers, as the envelopes shown, are fed by our mechanism one at a time to the platen, and after being written on by the 60 typewriter, are conveyed by the bands against which they are held by spring-pressed rolls 31, 43, and through suitable guides 32 for their edges, and are delivered into a paper holder comprising lateral members 33 carried respectively by the secondary

frame's lateral members 10. A stop 34, adjustable to accommodate papers of different dimension in the direction of their delivering movement of the paper holder, is adapted to arrest such movement, and is adjusted to a position nearer a portion of the arcuate movement of the band over the uppermost roll 13 than the dimension of the papers in the direction of their delivering movement, so that the lower edge of the papers may, by the engagement of the moving band, be bent backwardly, thus providing an entering space or sufficient clearance 35 for the ready and unobstructed delivery of succeeding papers to 80 the holder. A spring-pressed retaining member 36 is adapted to retain the paper bcdy 37 in said holder and to yieldingly admit the papers thereto. At the point of the delivery from the band to the paper holder, the papers are (as shown in Fig. 3) deflected from the direction of their previous movement by means of a deflector, (which in the construction shown is the uppermost roll 43), thus insuring their ready introduction 90 into the holder, each successive paper next to the one last introduced.

To readily apply our feeding mechanism to various typewriters, we provide a chuck 38 split to form fingers 39 adapted to receive and hold the end of the platen or its shaft 44. This chuck has a surrounding sleeve 45 whose interior wall is in inclined relation to the fingers. A screw 46 is threaded in the chuck and has a washer 47 holding the handle 48 in position, and is adapted to move the sleeve longitudinally relatively to the clutch, in order to compress the fingers on the platen's shaft. The secondary frame's lateral members 10 have T-shaped slots 49, 105 wherein the supporting portions 50 of guides 51 engage; these guides have spring arms 52 and are adapted to be turned in the slots, as shown in dotted lines in Fig. 9, to move them out of the way, etc. The followers 16 being 110 pushed back to and held in the position shown in dotted lines in Fig. 3, papers (as envelopes 15) are placed in the guides 14, whereupon, the follower being released, they are pressed against the bands. The platen 115 being turned, as in the ordinary operation of the typewriter, that paper which is engaged by the portion 22 of the bands is slipped off from the rest of the paper body 22 and fed to the platen where it is written 120 on by the typewriter: further rotation of the platen carries this paper by the bands, between the guides 32, and delivers it into the paper holder, and at the same time conveys other papers to the platen, one at a 125 time.

Not confining ourselves to details of construction shown or described, we claim:

1. In a paper feeding mechanism for a typewriter having a rotatable platen, a 130

movable member spaced from the platen and from the typewriter's types and adapted to frictionally engage the papers of the paper body successively and both feed the same to and convey the same by such frictional engagement from the platen.

2. In a paper feeding mechanism for a typewriter having a rotatable platen, a movable member spaced from the platen and from the typewriter's types and adapted to frictionally engage the papers of the paper body successively and both feed the same to and convey the same by such frictional engagement from the platen, and 15 means for actuating said member in connection with the rotation of the platen.

3. In a paper feeding mechanism for a typewriter having a rotatable platen, a band spaced from the platen and from the typewriter's types and adapted to frictionally engage the papers and both feed the same to and convey the same by such frictional engagement from the platen.

4. In a paper feeding mechanism for a typewriter having a rotatable platen, a band spaced from the platen and from the typewriter's types and adapted to frictionally engage the papers and both feed the same to and convey the same by such frictional engagement from the platen, and means for actuating said band in connection with the rotation of the platen.

5. In a paper feeding mechanism for a typewriter having a platen, a shaft parallel 35 to the platen's axis and carrying a pair of rolls, one of which is splined thereon, a pair of rolls axially parallel with the shaft's rolls and in corresponding position respectively thereto and one being axially movable correspondingly to said splined roller, and bands carried by the corresponding rolls of the two pairs and adapted to engage the papers and move the same relatively to the platen.

45 6. In a paper feeding mechanism for a typewriter having a rotatable platen, a pair of bands spaced from the platen and carried on rolls axially parallel with the platen, bands carried by the rolls and supported independently of the platen and adapted to frictionally engage the papers and both feed the same to and convey the same by such frictional engagement from the platen, a guide adapted to hold the papers and to 50 guide them to the bands, and a paper-holder adapted to receive the papers from the bands after being conveyed from the platen.

7. In a paper feeding mechanism a typewriter having a rotatable platen, rolls axially parallel and carrying a band adapted 60 to frictionally engage the papers and move the same by such frictional engagement relatively to the platen, and a guide adapted to hold the papers and to guide them to the band, and spring-actuated means for press-

ing the paper bodily in the guide against the tangential portion of the bands between the rolls.

8. In a paper feeding mechanism for a typewriter having a platen, a roll axially parallel with the platen and carrying a band supported independently of the platen and adapted to engage the papers and to feed the same to the platen, and a guide magazine adapted to hold the papers and to 75 guide them to the band, and means for adjusting the guide magazine bodily toward and away from the band.

9. In a paper feeding mechanism for a typewriter having a platen, a roll axially parallel with the platen and carrying a band adapted to engage the papers and to feed the same to the platen, and a guide supported pivotally axially-parallel with the roll and adapted to hold the papers and to guide 85 them to the band, and means for adjusting the guide on its pivot toward and away from the band.

10. In a paper feeding mechanism for a typewriter having a platen, a roll axially parallel with the platen and carrying a band adapted to engage the papers and to feed the same to the platen, and a guide supported pivotally axially-parallel with the roll and adapted to hold the papers and to 95 guide them to the band, and a screw for adjusting the guide on its pivot toward and away from the band.

11. In a paper feeding mechanism for a typewriter having a platen, a movable member adapted to engage the papers and to feed the same to the platen, and a guide adapted to hold the papers and to guide them to said member and having a follower guide, and a spring-pressed follower having 100 a partially rotatable and also a sliding movement in the follower guide toward and away from the movable member, the follower and the follower guide having parts co-engaging in one position of the follower to hold the same against its spring.

12. In a paper feeding mechanism for a typewriter having a platen, a movable member adapted to engage the papers and convey the same from the platen, and a paper 115 holder adapted to receive the papers from the movable member and having a stop adapted to engage the papers and hold the same against further movement while the same are still engaged by the movable member.

13. In a paper feeding mechanism for a typewriter having a platen, a movable member having an arcuate movement and adapted to engage the papers and convey 125 the same from the platen, and a paper holder adapted to receive the papers from the movable member and having a stop located nearer one portion of the movable member's arcuate movement than the dimension of 130

- the papers in the direction of their delivering movement to the paper holder and adapted to hold the papers against further movement in such direction.
- 5 14. In a paper feeding mechanism for a typewriter having a platen, a roll, a band carried by the roll and adapted to engage the papers and convey the same from the platen, and a paper holder adapted to receive the papers from the band and having a stop located nearer one portion of the band in its curved position on the roll than the dimension of the papers in the direction of their delivering movement to the paper holder and adapted to hold the papers against further movement in such direction. 70
- 10 15. In a paper feeding mechanism for a typewriter having a platen, a roll, a band carried by the roll and adapted to engage the papers and convey the same from the platen, and a paper holder adapted to receive the papers from the band and having a stop adapted to hold the papers against further movement in the direction of their delivering movement to the paper holder, and a spring-pressed retaining member adapted to retain the paper body in the paper holder and to yieldingly admit the papers to such holder under the action of the band. 80
- 15 16. In a paper feeding mechanism for a typewriter having a rotatable platen, a movable member adapted to engage the papers and convey them in a predetermined direction from the platen, a paper holder adapted to receive the papers from the movable member, and a deflector adapted to deflect the papers from such predetermined direction at the point of their delivery to the paper holder by bending the papers at such point. 90
- 20 17. In a paper feeding mechanism for a typewriter having a platen, a frame supported in connection with the platen and carrying a shaft and a guide rod both parallel with the platen's axis, a secondary frame carried by the shaft and guide rod and comprising lateral members each carrying a guide and a roll on the shaft, one such roll being splined, bands carried by the rolls and adapted to engage the papers and feed them to the platen, the guides being adapted to hold the papers and guide them to the bands, and one of said lateral members being adjustable on the shaft and guide rod toward and away from the other lateral member. 100
- 25 18. In a paper feeding mechanism for a typewriter having a platen, a frame supported in connection with the platen and carrying a shaft and a guide rod both parallel with the platen's axis, a secondary frame carried by the shaft and guide rod and comprising lateral members each carrying a guide and a roll on the shaft, one such roll being splined, bands carried by the rolls and adapted to engage the papers and feed them to the platen, the guides being adapted to hold the papers and guide them to the bands, and one of said lateral members being adjustable on the shaft and guide rod toward and away from the other lateral member. 105
- 30 19. In a paper feeding mechanism for a typewriter having a platen, a frame supported in connection with the platen and comprising supports having connecting members, a secondary frame carried by said connecting members, and a movable member carried by the secondary frame and adapted to engage and move the papers relatively to the platen, the said supports being adjustable on the connecting members toward and away from each other. 115
- 35 20. In a paper feeding mechanism for a typewriter having a platen, a frame supported in connection with the platen and carrying a movable member adapted to engage the papers and move them relatively to the platen, the frame carrying a member having a T-shaped slot, and a guide adapted to guide the papers in their said movement and comprising a pair of spring arms having supporting portions engaging in said slot and adapted to be moved therein in the longitudinal direction of the platen and against their spring pressure. 120
- 40 21. In a paper feeding mechanism for a typewriter having a platen, a frame supported in connection with the platen and carrying a feed-operating shaft axially parallel with the platen, an adjustable chuck having fingers adapted to receive and securely hold the end of the platen, a sleeve surrounding the chuck's fingers and having an interior wall in inclined relation to the fingers, means for adjustably holding the sleeve longitudinally relatively to said fingers, and rotary motion transmitting connections between the chuck and the feed-operating shaft. 125
- 45 22. In a paper feeding mechanism for a typewriter having a platen, a frame supported in connection with the platen and carrying a feed-operating shaft axially parallel with the platen, an adjustable chuck having fingers adapted to receive and securely hold the end of the platen, a sleeve surrounding the chuck's fingers and having an interior wall in inclined relation to the fingers, a screw for adjustably holding the sleeve longitudinally relatively to said fingers, and rotary motion transmitting connections between the chuck and the feed-operating shaft. 130
- 50 23. In a paper feeding mechanism for a typewriter having a platen, a frame supported in connection with the platen and carrying a feed-operating shaft axially parallel with the platen, sprocket wheels carried

by the platen and the shaft, a chain carried by the wheels, connected arms adapted to rock at their free ends relatively to the platen's and the shaft's axes respectively, and a chain carried by the arms in such position as to hold the chain between the wheels within its tangential direction.

24. In a paper feeding mechanism for a typewriter having a rotatable platen, a magazine adapted to hold a paper body comprising several papers, a member at the side of the platen and adjacent the magazine and movable rotatably in axially parallel relation to the platen's axis and adapted to engage the papers of the paper body successively and feed the same to the platen and subsequently engage such papers and remove the same from the platen, and guides for the papers in their said feeding and removing movement.

25. In a paper feeding mechanism for a typewriter having a rotatable platen, a magazine adapted to hold a paper body comprising

separate papers, a driven band at the side of the platen and adjacent the magazine and carried on rollers axially parallel to the platen's axis and adapted to engage the papers of the paper body successively and feed the same to the platen and subsequently re-engage such papers and remove the same from the platen, and guides for the papers in their said feeding and removing movement.

In testimony whereof we have hereunto set our hands in presence of two subscribing witnesses.
